UNITED STATES PATENT OFFICE.

WALTER HARDIE FINLEY, OF FAIRMONT, WEST VIRGINIA, ASSIGNOR TO FAIRMONT MINING MACHINERY COMPANY, OF FAIRMONT, WEST VIRGINIA, A CORPORATION OF WEST VIRGINIA.

SAFETY-GATE FOR MINE-SHAFTS.

1,276,199.

Specification of Letters Patent. Patented Aug. 20, 1918.

Application filed February 19, 1918. Serial No. 218,054.

To all whom it may concern:

Be it known that I, WALTER H. FINLEY, a citizen of the United States, residing at Fairmont, county of Marion, State of West Virginia, have invented certain new and useful Improvements in Safety-Gates for Mine-Shafts, of which the following is a specification.

This invention relates to automatic gates employed in connection with lifts or hoists and particularly mine shaft elevator cages.

One of the objects of the invention is to provide means whereby the gate operating mechanism may be rendered effective for operation from a distant point as, for example, within convenient reach of the hoisting engineer.

Another object of the invention is to provide means whereby when the hoisting mechanism is set for operation, the gate will be opened when the cage reaches a predetermined level, but will be automatically closed when the cage passes beyond such level. The setting of the gate operating mechanism to permit it to open is controlled by an electro-magnetic device illustrated as a solenoid. When the solenoid is not energized the mechanism for opening the gate cannot be thrown into operation.

80 In the drawings:—

Figure 1 is an elevational view of a gate operating mechanism constructed in accordance with my invention;

Fig. 2 is an edge elevation of the same;

85 Fig. 3 is a plan view of the gate operating mechanism;

Fig. 4 is an enlarged detail view of the break joint for the clutch operating rod;

Fig. 5 is a sectional view on the line 5—5 90 of Fig. 4;

Fig. 6 is a sectional view on the line 6—6 of Fig. 1;

Fig. 7 is a detail view of the gate tilting mechanism;

45 Fig. 8 is an enlarged top plan view of the gate hoisting mechanism;

Fig. 9 is an enlarged side elevational view of the gate operating mechanism;

Fig. 10 is a plan view looking down from 95 the plane 10—10 of Fig. 9;

Fig. 11 is a detail perspective view of the clutch throwing mechanism;

Fig. 12 is a detail perspective view of the gate retaining mechanism; and

Fig. 13 is a detail view of a presser foot 55 to release the clutch.

Referring now to the drawings by numerals of reference, 1 designates a standard on which are brackets 2 and 3 which support respectively the top and bottom rails 4 60 and 5 of the gate 6, said rails being pivoted to the brackets in any well known manner. On the upper end of the standard 1 is a machine base 7 upon which is mounted a motor 8, the shaft 9 of which is provided with a pinion 10 meshing with a gear 11 on shaft 12, in bearing 13, which shaft also carries a gear 14 meshing with a gear 15 on the shaft 16 upon which is loosely mounted a winding drum 17 adapted to be clutched to 70 the shaft through the clutch 18 and its actuator 19 in the usual manner when it is desired to wind the cable 20 thereon, but when it is desired to release the cable the clutch actuator will be moved away from its clutch 75 as is well understood.

It is desirable to provide means under the control of the hoisting engineer whereby the parts can be caused to operate, or be rendered inoperative according to the prevailing conditions. The motor 8 is shown as a reversing motor provided with the conductors 21 and 22 for the ahead motion and 22 and 23 for the reverse motion. In the circuit including the conductor 21 is an electro-magnetic device shown as a solenoid 24 on the bracket 25 carried by the standard 1. The core 26 of the solenoid is provided intermediate its ends with a head 27 having a vertical elongated slot and between the head and the solenoid coil is a spring 29 mounted to oppose the magnetism of the coil to normally move the head away therefrom, upon a guide pin 30 projecting from the head and through a guide bracket 31 on 95 the standard 1. Adjacent to the standard 1 and substantially parallel therewith is a vertical reciprocating clutch actuating rod 32 which extends nearly the entire length of the standard and through the base 7. 100 The rod 32 is provided with a shoulder or collar 33 against one end of which a coil spring 34 bears, the other end of the spring acting against the base 7 so that there is a

normal tendency to depress the rod 32 to make it slide in a downward direction in its guides 35. Near the upper end of the rod 32 is a slot 37 in which is positioned one end 5 of the lateral arm 38 of the bell crank lever 39 pivoted to the base 7 and having its other arm 40 connected to the lever 41 pivoted intermediate its ends as at 42 to a floating bracket 43 on a longitudinal shifting rod 10 44. The upper end of the lever 41 is bifurcated as shown at 45 to embrace clutch actuating member 19 so that when an upward movement is imparted to the arm 38 of the bell crank 39 and as the arm 40 moves from 15 right to left the bifurcated portion of the lever 41 will move from left to right and cause the clutch 18 to connect the drum to the shaft 16. An upward movement may not be imparted to the shaft 32 unless the solenoid 20 is energized because between the major portion of the rod 32 and its end 32' are the toggle levers 46 and 47, the outer respective ends of which are connected to the rod 32 and its end 32' and the inner ends of which 25 are connected by a pivot pin 48 in the vertical slot 28 so it will be seen that when the solenoid is not energized and the parts are in the position shown in Fig. 4, any upward movement imparted to the end 32' will 30 simply communicate motion to the toggles without effecting any corresponding movement in the rod proper 32. When, however, the solenoid is energized, the toggle levers will be brought into vertical alinement with the rod 32 and its end 32' so that 35 when the wheel 49 on the mine cage 50 comes into contact with the depending arm 51 of the elbow lever 52, the lateral arm 53 will impart an upward reciprocatory movement 40 to the end 32', the two toggle levers and the rod 32 against the action of the spring 34 to throw in the clutch 18. When the clutch 18 is thrown in (this being at the time that the cage is at the proper level), the drum 45 will start to be wound by the motor 8, previously energized, so that the cable 20 connected to the forward end of the gate 6 will cause it to tilt, the stop projection 55 coming in contact with the cam 56 will cause the 50 gate to fold up or collapse because the vertical bars 6' are pivoted to the rails 4 and 5 respectively. The elevation of the gate will continue until the pusher foot 57 comes in contact with a bolt 58 on the base 7 and by 55 imparting a reciprocatory movement to said bolt 58, the link 59 engaging the slot 60 in the sliding shaft 44 will impart a longitudinal movement to the set shaft 44. The longitudinal movement imparted to the shaft 44 60 must result when a transverse movement is imparted to the bolt 58 for the reason that the link 59 is at an angle to the bolt with its thrust in the direction of the length of the shaft. This shifts the floating bracket 43 65 from right to left (Figs. 8 and 11) so that the clutch 18 will be thrown out. It will be apparent, therefore, that even though the motor is operating at such time the drum will be disconnected from its shaft 16. By reference to Fig. 12, it will be observed that 70 the upper end of the shaft 32 is split at 62 to engage a slotted crank 64 which carries a bracket 65 supporting a retaining pawl 66. Therefore, when the rod 32 is raised the retaining pawl 66 will be depressed so as to 75 engage the end of the gate in its open position. When, however, the cage 50 moves away from the level and the solenoid is de-energized, the spring 29 will force the toggles into the position shown in Fig. 4 with 80 the result that the rod 32 will be depressed causing the crank 64 to rock the detent 66 out of contact with the gate so that it may close as shown in Fig. 1 as the pusher 57 moves away from the bolt 58, the spring 67 85 bearing against the collar 68 on the shaft 44 will shift the shaft from left to right to bring the floating bracket 43 into position to permit the clutch to be operated the next time the cage reaches the proper position 90 with respect to the level guarded by the gate 6.

If desired, signal lights may be included in circuit, an example of which is shown in Fig. 1 as is indicated at 69. 95

I claim:—

1. A gate operating mechanism comprising a driving means and a driven means, a device for connecting and disconnecting the driving means to and from the driven means, an actuator for the device responsive to a lift cage, means for normally preventing functioning of the actuator, and means to cause the actuator to function. 100
2. A gate operating mechanism, comprising a driving means and a driven means, a device for connecting one to the other, an actuator responsive to a lift cage for actuating the device, said actuator being normally inoperative and an electro-magnetic means 105 provided with distant control to render the actuator operative. 110
3. A gate operating mechanism comprising a winding drum, a motor driven shaft for said winding drum, a clutch interposed between the motor driven shaft and the winding drum, an actuator for the clutch, comprising a reciprocatory rod having an end and flexible connection between the said rod and said end, means for rendering said 115 flexible connection rigid and means responsible to a lift cage to impart a reciprocatory movement to said end when the flexible connection is temporarily rendered rigid. 120
4. A gate operating mechanism comprising a winding drum, a motor for operating it, a clutch between the winding drum and the motor, a clutch actuator comprising a rod, a flexible connection between the end of the rod, means for temporarily rendering the 125 130

flexible connection rigid, and means responsive to a lift cage for actuating said rod when the flexible connection is rigid.

5. A gate operating mechanism comprising a winding drum, a clutch means for actuating said clutch, comprising a reciprocatory rod, a lever interposed between the rod and the clutch, a floating bracket to which said lever is pivoted, whereby the movement 10 of the rod in one direction will cause the lever to throw in the clutch and means effective when the drum has reached the limit of its predetermined winding movement to shift the floating bracket to throw out the 15 clutch.

6. A gate operating mechanism comprising a standard, a winding drum on said standard, a motor for actuating said drum, a clutch interposed between the motor and 20 the drum, an actuator for said clutch comprising a rod, a connection between the actuator and the clutch including a pivoted lever, one end of which is connected to a clutch member and the bracket in which the 25 lever is pivoted, a gate actuated means for shifting the shiftable bracket and a gate engaging detent responsive to the upward movement of the rod to engage the gate.

7. A gate operating mechanism comprising a winding drum, and a motor therefor, 30 means for connecting and disconnecting the drum and motor, including a reciprocatory rod, a toggle joint between the ends of the rod, a solenoid for alining the toggle levers 35 with the two parts of the rod whereby a movement imparted to one part of the rod will be imparted to the other and means for imparting movement to one of the rod parts.

8. The combination with a standard, of 40 an upwardly swinging folding gate pivotally supported by said standard, a winding drum at the upper end of the standard and having a cable, one end of which is connected to the forward end of the gate, a motor for operating 45 said drum, a clutch between the drum and the motor, a rod slidably supported by the standard, clutch operating elements coöperating with said rod and comprising a shifting bracket, a lever pivoted 50 intermediate its ends to said bracket, one end of which is connected to the rod, a longitudinally sliding rod connected to the shiftable bracket to impart a sidewise movement thereto, a bolt for operating said rod 55 and responsive to pressure exerted by the gate when it is moved to its collapsed posi-

tion, a swinging gate detent, and a connection between the detent and rod whereby the movement of the rod in one direction will move the detent into gate engaging position 60 and the movement of the rod in opposite direction will move the detent into gate releasing position.

9. The combination with a standard, of 65 a machine base on said standard, a winding drum supported by said base, and a motor for operating it, a clutch for connecting and disconnecting the motor and the drum, and including a pivoted clutch lever, a swinging 70 gate, a swinging gate detent for engaging the upwardly swinging gate when raised by the drum, and an upwardly sliding rod connected to the clutch lever, throwing the clutch and connected with the detent to move it into gate engaging position. 75

10. In a gate operating mechanism, an 80 electric circuit, a motor in the circuit and an electro-magnetic device in the circuit, a gate opening mechanism comprising a winding drum having a cable for attachment to a gate, means for connecting the drum to the motor, an actuator therefor comprising a reciprocatory rod, means normally rendering the rod inoperative, and means coöperating with the rod and electro-magnetic device to render the rod operative when the electro-magnetic device is energized and the motor is rotating. 85

11. In a gate operating mechanism, a motor, a winding drum having a cord for engagement with the gate, a clutch between the motor and the drum, a clutch actuator, a gate detent connected to the clutch actuator and movable into operative position 90 when the motor and drum are clutched together, and means responsive to a lift cage for actuating said actuator. 95

12. The combination with a motor, a winding drum and a clutch for connecting the two, of a clutch operating mechanism 100 comprising a reciprocatory rod, a bell crank lever, a floating bracket, a lever pivoted in the floating bracket and engaging a clutch member, a sliding rod to which the bracket is secured and spring-pressed in one direction, and means for shifting said rod against the action of the spring. 105

The foregoing specification signed at Fairmont, W. Va., this 30th day of January, 1918.

WALTER HARDIE FINLEY.
